UNITED STATES PATENT OFFICE.

ALEXANDER E. BROWN, OF CLEVELAND, OHIO, ASSIGNOR TO THE BROWN
HOISTING MACHINERY COMPANY, OF CLEVELAND, OHIO.

MEANS FOR HOISTING AND CONVEYING TWO-ROPE GRAB-BUCKETS.

No. 829,057.

Specification of Letters Patent.

Patented Aug. 21, 1906.

Application filed February 10, 1906. Serial No. 300,455.

To all whom it may concern:

Be it known that I, ALEXANDER E. BROWN, a citizen of the United States, residing at Cleveland, in the county of Cuyahoga and State of Ohio, have invented a new and useful Means for Hoisting and Conveying Two-Rope Grab - Buckets in Connection with Overhead Tramways, as to which I hereby declare the following to be a full, clear, and exact description, due reference being had and intended to the drawings accompanying and made a part of this specification.

My invention relates to and involves the special kind of appliances chiefly employed in hoisting and conveying what is known as the "two-rope" type of grab-bucket on and in connection with overhead tramways for the purpose of transferring ore, coal, or other gross material from car or boat to stock-pile, and vice versa. In this operation the bucket is raised and lowered by the alternate winding up and paying out of the so-called "hoisting" and "bucket-sustaining" or "shell" ropes, respectively, and is then traversed along the bridge-tramway that spans the field of operations by means of a special racking rope and drum, which drum, as well as drums, respectively, for the hoisting and the shell rope referred to are each controlled through clutches and brakes that are controlled by electric circuits manipulated by levers located at a common point. In prevailing methods a given grab and dump involves the exercise of no less than six distinct lever movements on the part of the operator, each in prescribed and rapid sequence, and with a change and shifting of grasp and posture each time. The bucket being above the hatch, with jaws distended ready for its load, the operator first presses a foot-lever to free the hoisting-drum and allow the bucket's descent by gravity. He next moves a second lever to throw out the clutch between the hoisting and shell or bucket-sustaining drum and at the same time pushes out a third lever to clutch the hoist-rope drum to the driving-shaft. A fourth lever must now be seized to start the shaft, and when the latter's revolutions have caused enough of the hoist-rope to be wound up to close the bucket's jaws or blades it is necessary to at once actuate the levers that clutch both hoist and drums together on their shaft, so that their

respective ropes or cables shall thereafter take in at equal pace. When by this process the bucket is raised to its trolley, the drums must then be unclutched from the shaft and at the same time a lever be moved to rack the load along the tramway to the dumping-point, when by separate movements brakes are set in order to firmly lock the racking and the shell-rope drum, while the bucket empties itself.

It is the object and aim of my present invention to substitute for the arrangement just described a mechanical method of accomplishing the same results, but with a greatly-reduced number of levers and a corresponding reduction and simplification of the movements that an operator is called on to make.

In the accompanying drawings, Figure 1 is a longitudinal sectional view of a hoist-rope and a shell-rope drum as mutually related in their normal place upon a drive-shaft, together with the lever and lever connections that control their movements. Fig. 2 is a like view of a single racking-drum as employed in my said method. Fig. 3 is an enlarged detail of the hand-lever, controller, and electric connections thereof shown in Fig. 1. Fig. 4 is a like detail of similar parts shown in Fig. 2, together with the brake-band and bell-crank connection pertaining to the same, the said band being represented as set. Fig. 5 indicates the lever, bell-crank, and band connections shown in Fig. 4, when the brake-band is off. Fig. 6 is a diagrammatic plan view of a preferential order for the placing of the levers shown. Fig. 7 is a side elevation of a hoisting and conveying machine or overhead system containing as elements thereof various features shown in the preceding figures when such features are located in the supporting-frame of said machine, and Fig. 8 is a similar view when the trolley-track is arranged horizontally of said frame (instead of on an incline with respect thereto, as in Fig. 7) and certain of the features previously shown are located in the trolley carried by such track.

Similar reference characters are used on the same parts throughout the drawings.

B is the hoisting and conveying machine or overhead system as a whole.

In said drawings, D and D' are drums car-

rying, respectively, the hoist and the bucket-sustaining or shell ropes d and d' . Around their outer ends braking facilities are provided, as indicated by the brake-shoes b b' and brake-bands b^2 b^2 . Said drums are mounted loosely on the drive-shaft A through their hubs h and h' , respectively, and, as shown, have their inner ends in close juxtaposition one to the other.

10 Below and concentric with the drum D at its outer end there is mounted the disk C of a friction-clutch device. The clutch shown in the drawings is of that order of such devices where the circumferential surface of an annular band or fillet that surrounds and is fastened to a shaft-wheel is moved into forcible contact with a peripheral surface of the part to be driven by distending such band oppositely from its ends. Between the perimeter of the wheel C and the drum D is the band of such clutch, (denoted in the drawing by c .) and fastened to the under surface of the drum D is a thicker fillet or band of wood, vulcanized fiber, or like material c' , which serves as the shoe or bearing-surface with which the clutch-band comes in contact when the clutch is thrown in.

15 As indicated by dotted lines, the wheel C is keyed or splined to the shaft A through its hub h^2 . A similar clutch-wheel C' , with corresponding clutch-band c^2 and shoe c^4 , is indicated as concentric with the opposite exterior end of the drum D , or, rather, with an annular flange that projects from that end within and concentric with the end of the drum D' . The wheel C' differs, however, from the wheel C in that its hub is a prolongation of or is fixed to and within the hub proper of the drum D' , and consequently is not keyed to the shaft A , 20 but is mounted loosely thereon and turns with and as a part of said drum.

25 d^2 is a sliding collar around the hub h^2 , adapted to throw the clutch in and out as it is reciprocated, and d^3 is a corresponding collar connected by the rods r r with the outer sliding collar D^2 .

30 L is a forked clutch-lever that straddles the collar d^2 and is pivoted at the fixed point p . The branches or forks of said lever embrace and engage the collar d^2 , and its lower arm is connected by the link-pieces l l with the solenoid S . Similarly L' is a forked clutch-lever that embraces the collar D^2 . Its upper arm is connected, as with the link-piece F^2 , with an operative handle H' , and when said handle is used p' becomes the fixed point for the lever L' . When operated by the solenoid S' , as hereinafter explained, its fixed point p will be at p' .

35 S is a solenoid connected by the links l' l' with the lever-arm L at f . Its circuit (represented by the lines e e') comprehends the handle-bar H^2 and a switch or current-interrupter therein i , (in dotted lines,) actuated

40 by an electric button k , located on said handle-bar. Said circuit further comprehends an intermediate switch w' and an operative solenoid therefor s' . Said handle-bar H^2 is duly fitted to be oscillated about a point o and has its lower end provided with a shoe U of any suitable conductive material. Said shoe is preferably given a convexity at its outer face or surface corresponding with its orbital movement around the center o and is duly connected with the circuit (represented by the lines e e') of the solenoid S . In the same circuit and so located that when the handle-bar H^2 is reciprocated the shoe U will be traversed across the same in bearing or contact therewith is a second concentric-shaped shoe U' . The circuit is further interrupted by an intermediate switch w and an operative solenoid therefor s .

45 M is a motor for driving the shaft A . It is governed by the controller N through the circuit represented by the lines m m . Said controller is adapted to be actuated by oscillating the handle-bar H^2 , with which it is connected by the lever-arm or link-piece G , supported in the guides g g and the boot-lever T . 50 To compensate for the parallel motion of the lever-arm G , at the same time insuring, as will be seen, that the clutch on the hoist-drum D is in before the shaft A is started, a slot t , with a proportioned upturn (see Fig. 3) 55 is formed in said boot, in which slot the end of the lever-arm G is duly seated and slides.

55 P represents the trolley, of a kind suitable for use on an inclined track, as indicated in Fig. 7 by V , and P' a trolley—in this case 60 of the so-called "man-trolley" type—carrying within itself the hoist-drum, bucket-sustaining drum, motors, clutching devices, circuit-breaking apparatus, and levers for controlling the same, described.

65 D^3 is the usual racking-drum for taking in and letting out the racking-rope d^4 . It is fast to the shaft A' , which is driven by the motor M' and is provided with a brake, (indicated by the brake-shoe f^3 and the brake-band b^4 .) The latter—the brake-band b^4 —is connected with the handle-bar H by the bell-cranks e^2 and link-pieces e^3 in any suitable manner, as shown in Figs. 4 and 5, to enable it to be actuated at will.

70 The motor M' is governed by the controller N' through a circuit represented by the lines m' m' by means of the handle-bar H and the sliding lever-arm G' and boot-lever g' , connecting the same. R is a reversing-lever on said controller adapted to be moved from a normal by the solenoid S^2 , whose circuit (represented by the lines f^2) is connected with the handle-bar H and is there subject to a circuit-interrupter or switch i' , (shown in dotted lines,) actuated by an electric button k' in the handle proper or grasp of said handle-bar. Although there are shown the two switches W and W' as operating, respectively, the solenoids S and S' , by which arranged

ment a lesser current is required, nevertheless it is evident that either or both of said switches could be dispensed with and the wires e and e' connected directly with the 5 solenoids S and S' , as the conditions required, without departing from the principle of the invention, the switches i and U in and a part of the handle-bar H^2 being still required for its operation. It will be understood that 10 said handle-bars H , H' , and H^2 are each provided with the necessary facilities for setting them at will in their respective quadrant-stands, so as to afford the necessary resistance, through their various bell-crank and 15 levers, to and against any opposite action of the solenoids with which they are connected, also that said levers are assembled in the order perhaps indicated in Fig. 6 at some common point convenient for their handling.

20 Having thus described my said invention, its operation is thus explained: Assume, as to the drawings, that the bucket is empty and suspended immediately below its tramway above the loading-point with jaws dis- 25 tended and hoist and bucket-sustaining drums, as shown, in clutch together. Under these conditions the bucket is allowed to descend by gravity under control of the brake of the drum D' , during which operation both 30 hoist and shell-ropes d and d' will be paid out at equal pace. On reaching and resting on the stock-pile, by pressing the button k on the handle-bar H^2 the so-called "shell-clutch" will be thrown out and the hoist-drum D , the 35 drum whereby the bucket is closed and hoisted, will be free to move and close the jaws without a corresponding movement of the bucket-sustaining or shell drum D' and its rope. Without releasing his grasp at all the 40 operator, by simply throwing forward the lever H^2 to an upright position, will bring the shoes U and U' in bearing throughout a portion of their surfaces, and thereby close the circuit e and actuate the small intermediate 45 solenoid s , so that the switch w will be closed, the solenoid S actuated, and the hoist-drum D clutched to the drive-shaft A . By now further pushing the lever H^2 forward the last 50 motion of the lever-arm G will be taken up, the boot-lever T propelled, and the motor M started. The hoist-drum now takes up its rope d and both closes the bucket and brings it up to the trolley on the tramway overhead, pressure being removed from the button K at 55 the moment of closing in order to lock the two drums together and insure the winding in of both ropes at the same rate. The operator next propels the racking-lever H to a vertical, which releases the racking-drum 60 brake, and then by a further propulsion the controller may be actuated and the racking-drum motor M' started. The trolley and its suspended bucket is in this manner traversed along the tramway to the proper point for 65 discharge, when the operator has but to re-

verse his previous movements to accomplish all that is required for its return to the supply-point.

What I claim, and wish to secure by Letters Patent, is—

1. In a double drum for overhead tramways, the combination, with a drive-shaft of a hoist-drum and motor mechanism for driving the same, of a bucket-sustaining drum, and suitable means, respectively, for clutching said drums, one to the other, which means are controlled by a circuit-breaking apparatus on a hand-lever provided for the purpose, and a solenoid operatively related to the same, together with suitable means for clutching said hoist-drum to said shaft, the said means being controlled by an electric circuit connected with said hand-lever, which is made and broken according as said lever is reciprocated, substantially as shown 75 and described.

2. In combination with an overhead tramway system for hoisting and conveying, a hoist-drum, and a bucket-sustaining drum mounted on a shaft, adapted to drive the 90 same when actuated by an electric motor provided for the purpose, suitable means for, respectively, clutching one of said drums to said shaft, and each to the other, one of the means so provided, and said motor, being 95 controlled by a circuit-breaking hand-lever containing a second circuit-breaking apparatus that controls the other of said means, together with a suitable actuating appliance for said latter means on said lever accessible 100 to the operator's grasp, substantially as shown and described.

3. In a double drum for overhead tramways, the combination, with a drive-shaft and an electric motor for driving the same, of 105 a hoist-drum and a bucket-sustaining drum, suitable means for clutching one of said drums to said shaft, and each to the other, when electric circuits, with which each is connected, are made, switches in said 110 circuits, and solenoids to operate the same, a lever-arm so related to the circuits of said motor and shaft-clutching means as to enable said circuits to be successively made and broken and said solenoids to be operated according as said lever is reciprocated, the said 115 lever being also provided with an appliance in or on the handle thereof to break the circuit, with which it is connected, that actuates said means for clutching said drums together, substantially as shown and described.

4. In a double drum for overhead tramways, the combination with a drive-shaft and an electric motor for the same, of a hoist-drum and a bucket-sustaining drum, suitable means for clutching one of said drums to said shaft, and each to the other, when an electric circuit, with which they are connected, is made, a lever-arm so related to the 125 circuits of said motor and shaft-clutching 130

drums respectively as to successively make and break the same when duly reciprocated, the said lever being provided with an apparatus in or on the handle thereof, to break the circuit, with which it is connected, that actuates said means for clutching said drums together, substantially as shown and described.

5. In combination with an overhead tramway system for hoisting and conveying, a hoist-drum and a bucket-sustaining drum, mounted on a shaft, adapted to drive the same, when actuated by an electric motor provided for the purpose, suitable means for respectively clutching one of said drums to said shaft and each to the other, one of the means so provided, and said motor, being controlled by a circuit-breaking hand-lever containing a second circuit-breaking apparatus that controls the other of said means, together with a suitable actuating appliance on said lever for the same, substantially as shown and described.

6. The combination, with an overhead tramway, of a drive-shaft and actuating electric motor therefor, a hoist-drum and bucket-sustaining drum on said shaft, provided with suitable means for clutching one of said drums to said shaft, and each to the other, when an electric circuit, with which each is

connected, is made, a racking-drum, for said tramway, actuated by an electric motor, which said racking-drum and motor, are controlled by an electric circuit that is made and broken upon the reciprocation of a hand-lever provided for the purpose, all substantially as shown and described.

7. In a double drum for overhead tramways, the combination, with a drive-shaft and an electric motor for the same, of a hoist-drum provided with a suitable device for clutching said drum to said shaft, when an electric circuit with which it is connected, is made, a bucket-sustaining drum provided with a suitable device for clutching the same to said hoist-drum, when an electric circuit with which it is connected, is made, together with a hand-lever arranged to make and break successively electric circuits connected with said motor and said hoist-drum device when said lever is reciprocated, and, also, carrying an apparatus to make and break the electric circuit connected with said bucket-sustaining drum, substantially as shown and described.

ALEXANDER E. BROWN.
